TOOL FOR CLEANING AND POLISHING
TUBING ENDS AND FITTINGS

Leonard Witham, Oceanside, N. Y.

Application December 6, 1948, Serial No. 63,723

4 Claims. (Cl. 51—148)

1

The present invention relates to rotary tools, and is particularly concerned with a tool for cleaning and polishing tubing ends and fittings.

An important object of this invention is to provide a tool for facilitating the preparation of tubing ends and plumbing fittings to be sweated together with solder. Heretofore, plumbers have relied principally upon direct manual cleaning operations for this purpose, usually with a strip of fine abrasive cloth or with steel wool. Such an operation is time-consuming, and moreover, the plumbers often lack sufficient thoroughness in this manual cleaning to accomplish complete solder sealing of the joints. The external polishing of the tubing ends in this direct manual way is unsatisfactory both as to time consumption and as to results, and the internal cleaning of the ends of the fittings is even less satisfactory.

Acid bath devices have been proposed to alleviate these difficulties in achieving the thoroughly cleaned surfaces required for proper soldering, but these have proven cumbersome to use and hazardous to body and clothing, to such extent that they have failed to achieve widespread adoption in the trade.

Along with the major object of this invention to provide an efficient and safe tool for the rapid and thorough cleaning of tubing and fittings, further objects comprehended are to make a tool adapted for portability and compactness, and for a choice of hand-crank or motor drive operation.

The way in which this invention meets these objects as well as further objects and advantages will become apparent from the following detailed description of an embodiment of the invention, taken in conjunction with the accompanying drawings, wherein Fig. 1 is a front elevation of a version of the invention, Fig. 2 is a sectional view taken on the line 2—2 in Fig. 1, and Fig. 3 is a fragmentary sectional view of the interior polisher portion of the structure shown in Fig. 1.

The tool illustrated in these drawings comprises a housing 11 which normally stands upright as viewed in Fig. 1. It is arranged to receive the end of a length of tubing 13 for external polishing, or the end of a fitting 15 for internal polishing. For convenience in use, especially when hand cranked for cleaning fittings and short lengths of tubing, the tool may be clamped to a board 17 extending from a table top or a vise, a clamp 19 being provided for this purpose.

The hand crank 21 with a slip handle 23 is arranged to operate in a journal 25 formed in the housing 11. The crank shaft extends through

2

this journal 25 and has attached to its projecting end a master gear 27 which is arranged to mesh with three gears 29, 31 and 33 within the housing 11. Gears 29 and 31 are provided for driving an abrasive belt 35 employed for polishing the exterior end surface of tubing lengths, e. g. tubing 13, and gear 33 is provided for imparting rotation to the fitting interior polishing mechanism.

10 The abrasive belt 35 passes over four pulleys and loops around the end of the tubing 13, its uncoated fabric surface being in contact with the cylindrical surfaces of the pulleys and its abrasive coated surface being applied to the outer surface of the tubing end 13. Two of the pulleys 37 and 39, which preferably are rubber coated, are fixed to pinions 29 and 31, respectively, for impelling the abrasive belt 35; and the other two pulleys 41 and 43 are arranged as idler pulleys 15 provided on movable journal bases 45 and 47. These bases are fitted into keyways 49 and 51, and are urged upward by springs 53 and 55 which act to retain belt 35 under the desired tension.

15 A knurled or splined stub shaft 57 is fixed centrally to gear 27, for bearing against the external surface of the tubing under treatment, and for cooperating with the abrasive belt to rotate the tubing slowly as it is being polished, for even distribution of the polishing action.

20 A hardened steel pin 59 of appreciable diameter is fixed to a lever 61 pivoted at 63 and arranged for facilitating insertion of a tubing end (e. g. tubing 13) to be polished and removal thereof upon completion of the operation. This pin 25 59 has a taper skirt at its base for contacting the cut inner edge of the tubing and rolling out any burrs therefrom.

25 The lever 61 extends well beyond the pin 59, and at its end is coupled through a slip link 65, 65' to a scissors linkage 67 coupled to the movable journal bases 45 and 47. Symmetrical fixed pivots 69 and 71 are provided for the arms 73 and 75 of the scissors linkage 67, and a pin 77 in one of the arms is arranged to cooperate in a slot 79 in the other to effect concerted movement 30 of them and of the respective journal bases 45 and 47.

35 The slip link 65, 65' comprises two link portions, part 65 having two pins 81 and 85 there-in cooperating in a slot in the other part 65'. This arrangement is provided so that the lever 61 when in the handle-down position for pressing the tubing end in contact with the burred pin 57 is not closely coupled to the journal bases 50 45 and 47, but when the end of the lever 61 is

raised to increase the separation of pins 57 and 59 and permit removal or insertion of a tubing end, the lower part 65 of the slip link pulls the upper part 65' downward, in turn causing the bases 45 and 47 to be pulled downward, slackening the abrasive belt.

A fixedly positioned toothed sector 87 attached to the casing 11 and a cooperating toothed pawl 89 supported on the lever 61 and urged toward sector 87 by spring 91 are provided for holding lever 61 in the open or in the working position (i. e., with the right end up or with it down). A rightward hook-like extension of the pawl 89 is provided to facilitate withdrawal of the pawl to the right for free movement of the lever 61 as desired.

On the shaft of pinion 33 is provided a disc 93 having two symmetrically located pivots 97 and 99 anchored therein. On these pivots are provided two L-shaped arms 101 and 103. This assembly of disc 93 and arms 101 and 103 is shown more fully in Fig. 3. Each of these arms has a portion parallel to the disc 93 and a portion extending perpendicular thereto, the latter portion being provided with an abrasive convex coating. The ends of the L-shaped arms 101 and 103 opposite to the abrasive-coated parallel portions are pulled by tension springs 105 and 107 toward pins 109 and 111 anchored in the disc 93. These springs act to urge the abrasive coated parts of the arms outward, to provide pressure thereof against the inner surface of a fitting, e. g. fitting 15.

For use of the tool above described, the housing 11 is clamped to the support 17, and the end of a length of tubing 13 to be soldered or "sweated" in place is inserted in place for external polishing and internal burr removal. This is accomplished by raising the end of lever 61 and moving the tubing axially onto the pin 59, and thereafter lowering the end of lever 61 to press the tubing end against the knurled central pin 57, the pawl then being released to retain the lever so positioned.

With the lowering of the end of lever 61, the belt is brought up tight around the end of the tubing by the action of springs 53 and 55. Now the crank 21 is turned, producing revolution of the master gear 27 and simultaneous drive of the belt 35 and the knurled central pin 57. Belt 35 and pin 57 act in opposite torsional directions on the tubing, one tending to revolve it counterclockwise when the other acts to revolve it in the clockwise direction as viewed in Fig. 1. The knurled central pin prevails in determining the direction of rotation of the tubing, causing it to turn slowly in the direction of rotation opposite to that of the crank 21 while the abrasive belt 35 traverses the tubing surface at appreciably greater surface speed. Thus, the relative surface speeds of the tubing and the abrasive belt are higher than the speed of the belt. Through this action, the belt is effective to clean and polish the end of the tubing rapidly and efficiently, and the action on the tubing is uniformly effective all around.

The female ends of the fittings to be employed in conjunction with the tubing—i. e., the ends of the T's, elbows, unions, and other plumber's fittings—are subjected to internal polishing action on arms 101 and 103. For this purpose, the abrasive-coated perpendicular arm ends are manually sprung together and the fitting end is slipped thereover.

The ends of the arms 101 and 103 are then

75

released and permitted to be urged outward into pressure contact with the inner surface of the fitting end, and the crank 21 is rotated to provide rotation at appreciably greater velocity of the disc 93. Rapid and effective internal cleaning and polishing of the fitting end is thus achieved, and the fitting and tubing end are then in readiness to be sweated together with solder.

It will be readily apparent that the master gear 27 may be motor-driven through speed reduction gearing, and that a suitable clutch such as a belt slip clutch may be provided if desired for stopping and starting the mechanism at will without delay for stoppage and acceleration of the motor. It will be further apparent that a tubing end and a female fitting end may be polished simultaneously by the operation of this system.

As many changes could be made in the above construction and many apparently widely different embodiments of this invention could be made without departing from the scope thereof, it is intended that all the matter contained in the above description and shown in the accompanying drawings shall be interpreted as illustrative and not in a limiting sense.

What is claimed is:

1. A tool for rotary cleaning and polishing the exterior surfaces of tubing ends in preparation for a solder seal junction, comprising a base or housing, a shaft journaled therein, a master gear on said shaft, means for imparting rotation to said shaft and gear, a pair of pinions in mesh with said master gear to be driven thereby, a traction pulley on each of said pinions, a pair of idler pulleys, said traction pulleys and said idler pulleys being situated substantially according to a rectangular pattern encompassing said master gear with their axes parallel to said shaft, an abrasive belt passing around the traction pulleys and the idler pulleys and extending inward between said idler pulleys in a U passing around said shaft, and a pin supported between said shaft and the bottom of the U of said belt for receiving the end of a length of tubing and constraining it to be retained between the abrasive surface of the belt and the surface of said shaft, said shaft surface being a frictional surface, and said idler pulleys being movable toward said traction pulleys for accommodating various tubing diameters and being elastically urged away from said traction pulleys to provide pressure against the tubing, whereby rotation of said shaft provides dual friction action of said abrasive belt and said shaft on the tubing.

2. A tool as defined in claim 1, wherein said pin is supported by a pivoted lever arranged to be locked in position restraining said tubing against said shaft.

3. A tool as defined in claim 1, wherein said pin is supported by a pivoted lever arranged to be locked in position restraining said tubing against said shaft, said tool further including means comprising linkage between said lever and said idler pulleys for providing intercoupled movement of said pin and said idler pulleys, whereby said lever is enabled to retract said pin and said idler pulleys for simultaneously releasing said tubing from contact with said shaft and loosening said belt.

4. A tool for rotary polishing of tubing ends and fitting ends, comprising a base or housing, a master gear therein, a plurality of pinions meshed therewith, a plurality of pulleys attached to respective ones of said pinions, an abrasive belt driven by said pulleys, means for supporting and

revolving the end of a length of tubing in contact with said abrasive belt for exterior cleaning and polishing, a pair of idler pulleys movably supported adjacent said master gear opposite to said attached pulleys, said abrasive belt passing over said idler pulleys and the pulleys on said pinions, said means for supporting and revolving the end of a length of tubing including a pin positioned adjacent said master gear, said belt passing over said idler pulleys and down in a U to wrap substantially one-half around the tubing, and means elastically urging said idler pulleys outward to retain said belt taut.
